UNITED STATES PATENT OFFICE

2,136,210

METHOD AND APPARATUS FOR SYNCHRONIZING STRIP FEEDING AND FABRICATING MOVEMENTS

Edward H. Hall, Chicago, Ill.

Application October 2, 1937, Serial No. 166,967

6 Claims. (Cl. 164—87)

The mechanism of the present invention is designed to act upon stock in the form of a band or strip which is fed through a press or the like at a constant speed and without interruption in its rate of advance during the instant that the punch and die or other forming tool are in operation, thereby providing means for recurrently cutting, punching, or otherwise acting upon the stock at uniform intervals and at each cycle of operation.

In attaining the above results, the male and female members of the associated group are mounted to oscillate in unison upon a common center which at the operating point affords an arcuate line of movement approximating the movement of the stock, and this united oscillatory movement of the operating elements is combined with a reciprocatory movement of the elements in relation to one another, so that the forming or dieing operation will be performed while the operating elements are advancing with the stock itself, which avoids the necessity for intermittent feeding and thereby greatly simplifies the construction of the machine as a whole and enables it to operate at a rapid rate of speed.

Furthermore, by providing an oscillatory mounting for the forming or dieing elements, and by oscillating both of these elements upon a common center, the structure of the machine is greatly improved, and the accuracy of its operation is insured.

Further objects and details will appear from a description of the invention in conjunction with the accompanying drawings, wherein,—

Figure 1 is a perspective view of a die press involving the features of the present invention;

Figures 2, 3 and 4 are sectional elevations of the die press and mountings therefor, showing different positions in the cycle of operations; and

Figures 5 and 6 are similar views taken at right angles to the sections of Figs. 2, 3 and 4, respectively, showing the die members in separated relation and in closed relation.

The mechanisms which particularly form the subject matter of the present invention are capable of use in connection with cutting, dieing, punching, embossing, or forming machines of various types of construction, which may be employed either for punching holes at recurrent intervals in a continuously fed strip of material, or for pressing, or embossing, or reforming, or otherwise acting upon said material at recurrent intervals, or for wholly or partially

severing said materials into sections, or for recurrently acting upon a continuously advancing strip for the purpose of otherwise conditioning it.

For purposes of illustration, such mechanisms are shown as constituents of a walking punch and die, which comprises a vertically elongated frame 10 carrying at its upper end a shaft 11 operated by means of a drive wheel 12 and having at its inner end an offset crank pin 13 which journals a plunger 14 having in the form shown a male die member or punch 15. The male die member coacts with a female die member 16 in the form of a hardened block provided with an inverted conical bore 17 which registers with a longitudinal discharge duct or passage 18 formed through the center of an oscillating arm 19 and discharging laterally therefrom through an orifice 20.

The oscillating arm terminates in a journal 20 head 21 mounted upon a journal pin 22 carried between standards 23 upstanding from a base plate 24 rigidly secured to a platform 25 outstanding from the forward side of the frame 10 at a convenient level above the base thereof.

The lower end of the plunger 14 and the upper end of the oscillating arm 19 stand in aligned relation to one another, and the major axis of these two aligned members intersects the axis of movement of the oscillating arm 19. The plunger is reciprocally guided within a sleeve 26 which, as shown, is rigidly secured upon the oscillating arm 19 by means of a set screw 27. Near the upper end, the sleeve is provided with a lubricating ring 28 which affords a suitable bearing for the reciprocations of the plunger.

As shown, the oscillating arm 19 is provided at its upper end with a guide plate 29 which is secured in position by screws 30 entered into the end of the oscillating arm. The plate 29 is provided with a center aperture 31 which affords a clearance for the male die member or punch, and said aperture terminates in a transverse groove 32 which affords a guide slot 45 through which the strip of material is fed at a uniform rate of speed by any suitable and convenient means not shown.

It will be understood, of course, that the particular male and female die members above described are shown merely for the purpose of illustration, and that in lieu thereof other coacting members, such as cutters, embossing dies, forming tools, or other elements designed to act upon the strip, may be substituted, which are intended to 55

cut, deform, or otherwise modify the strip of metal or other material in the intended manner.

In operation, with the parts fitted and adjusted in the manner shown, a strip of material X is fed continuously through aligned apertures 33 in the sleeve 26 and through the groove 32 in the plate 29, which brings the strip into register with the operating elements provided to act upon it at recurrent intervals.

10 With the shaft 11 rotating at uniform speed, the plunger 14 will be reciprocated with relation to the oscillating arm 19, and since the plunger is guided within the sleeve 26, which sleeve in turn is carried by the pivoted arm 19, it necessarily follows that both the plunger and the arm will partake of the oscillatory movement occasioned by the revolutions of the eccentric crank pin 13, while at the same time maintaining a straight line reciprocatory relation to one another.

15 The parts are so fitted that the male element of the group will coact with the female element during each downward thrust of the plunger and be withdrawn therefrom during each upward or return movement of the plunger, so that on the acting stroke and at the instant of contact of the operating members with the strip, they will be advancing through an arcuate path which approximates the straight line movement of the strip, so that the operating elements, at the instant of contact with the strip, and while punching or deforming the same, will substantially partake of the feeding movement thereof. This permits the strip to advance continuously and at the same time permits the dies or tools to punch through or otherwise act upon the strip without interference by reason of appreciable divergence in the direction of movement of the parts.

20 The machine is intended primarily to act upon strips of material of a more or less flexible nature, so that the strips, in passing through the guide apertures in the oscillating sleeve, and through the groove or channel 32 in the oscillating arm 19, may ordinarily yield or flex slightly to accommodate the oscillatory movements, and it is desired to provide sufficient clearance to prevent binding or cramping of the material during its passage through the machine, though it is obvious that, where conditions require, the material itself may be guided through a slightly curvilinear path exactly coincident with the arc of movement of apertures through which the material is guided.

25 For most purposes, it suffices to provide for the oscillation of the parts on a radius of sufficient length to approximate the straight line feeding movement ordinarily imparted to flexible strips of material, and with the parts thus actuated, sufficient precision and uniformity in operation will be secured to meet ordinary requirements.

30 The main feature of the invention resides in the provision made for so mounting both the die elements that they will oscillate upon a single center while providing for the relative reciprocation of the dying or forming elements with respect to one another.

35 Of course, the spacing of the punches or deformations formed in the strip of material will depend upon the feeding speed of the material in relation to the speed of operation of the die members, and in all cases the parts will be so proportioned and arranged that the impact will occur at the instant while the forward component of oscillatory movement is at a maximum and substantially uniform with the speed of advance

of the material itself. After the instant of impact, the die or punch members will withdraw from one another, which will permit the necessary return oscillation of the parts in opposition to the direction of the feeding movement, which completes the cycle of operations.

40 The device is extremely simple and rugged in construction and in its functioning, since it utilizes the crank movement both for the purpose of providing the reciprocations necessary in the coaction of the male and female members, and at the same time affords the advancing movement necessary to synchronize and coordinate the operating parts with the continuous advance of the material at the instant of impact. The oscillating movements being thus centered upon a single center, there is no possibility of any maladjustment in the timing of the reciprocatory movements of the individual die members with their oscillatory movements in unison, so that accuracy 45 of adjustment and precision in operation will be attained.

45 Although the invention has been described with particularity as to detail, it will be understood that the mechanism above described serves merely by way of exemplification of the principles of operation, and that numerous modifications in detail may be made without departing from the spirit of the invention.

50 I claim:

55 1. In mechanism of the class described for recurrently acting upon a continuously advancing strip of material, the combination of a pair of forming elements and separate mountings for each of said elements, one of said mountings being adapted to impart oscillatory movements to its element upon a single center, means slidably connecting said forming elements, and means on the other mounting for imparting reciprocatory movements to its forming element concurrently with the oscillation of both of said elements, to bring the forming elements into coacting relation during the oscillatory advance of both of said elements in the direction of the feeding movement of the strip.

60 2. In mechanism of the class described for recurrently acting upon a continuously advancing strip of material, the combination of forming elements, means for guiding one of said forming elements to cause the same to reciprocate with relation to the other forming element, means for mounting one of said forming elements in position to oscillate upon a single fixed center concurrently with the reciprocation of the other forming element, and means for mounting and imparting synchronized reciprocating movements to the said other forming element and concurrently oscillating both of said elements in unison and in a direction approximating the direction of movement of the strip of material at the instant of impact of the forming elements.

65 3. In mechanism of the class described for recurrently acting upon a continuously advancing strip of material, the combination of forming elements, means for guiding one of said forming elements to cause the same to reciprocate with relation to the other forming element, means for mounting both of said forming elements in position to oscillate upon a single common center concurrently with the reciprocation of the reciprocating element, a single means for imparting synchronized reciprocating movements to the reciprocating element and concurrently oscillating both of said elements in unison upon

the same center and in a direction approximating the direction of movement of the strip of material at the instant of impact of the forming elements.

5. 4. In mechanism of the class described for recurrently acting upon a continuously advancing strip of material, the combination of forming elements, means for guiding one of said forming elements to cause the same to reciprocate with 5
10 relation to the other forming element, means for mounting both of said forming elements in position to oscillate upon a single common center concurrently with the reciprocation of the reciprocating element, and a crank for imparting 10
15 synchronized reciprocating movements to the reciprocating element and concurrently oscillating both of said elements in unison upon the same center and in a direction approximating the direction of movement of the strip of material at the instant of impact of the forming elements. 15

aligned relation to oscillate in unison on the fixed pivotal mounting of said arm upon the same center, the parts being correlated in such a way as to impart to the forming elements at the instant of impact with the material a forward advance approximating in speed and direction the continuous movement of the strip of material. 5

6. In mechanism of the class described for recurrently acting upon a continuously advancing strip of material, the combination of a frame, a shaft carried by the frame and provided with a crank, a reciprocating plunger mounted upon the crank and provided with a male forming element, an oscillating arm and a fixed pivotal mounting therefor, a female forming element carried by the oscillating arm in position to coact with the male element of the reciprocating plunger and to act upon the strip of material at the instant of nearest approach, a sleeve rigidly secured to the oscillating arm and extending outwardly therefrom in position to surround and guide the plunger in its reciprocatory movements toward and from the oscillating arm and for holding the parts in aligned relation to oscillate in unison on the fixed pivotal mounting of said arm, and said sleeve being apertured to permit the continuous passage of the strip of material therethrough and between the forming elements, the parts being correlated in such a way as to impart to the forming elements at the instant of impact with the material a forward oscillatory advance upon a common center, said advance approximating in speed and direction the continuous movement of the strip of material. 10
